WATER GUN

Filed Nov. 18, 1949

UNITED STATES PATENT OFFICE

2,589,977

WATER GUN

Jack Stelzer, New York, N. Y.

Application November 18, 1949, Serial No. 128,038

3 Claims. (Cl. 222—79)

1

This invention relates to liquid-spraying guns, such as are used as toys by children, and has for its object the provision of a toy gun of this character by means of which a stream of water may be sprayed for an appreciable distance by means of air pressure built up in a water-holding chamber or reservoir.

Another object of the invention is to provide, in a toy of this character, pump means which is conveniently operated to build up air pressure in a tank or reservoir to cause ejection of a stream of water when a trigger release is operated.

More particularly, the invention contemplates the provision of a gun of this character provided with a water tank to which a manually-operated air pump is connected, the pump being operated by movements of a portion of the body of the gun, the pump serving to build up air pressure inside of the water tank; the invention also including the employment of a suitable trigger-operated valve which, when opened, will cause a stream of water to be ejected out of an outlet pipe or tube having its outlet end located at the forward end or barrel of the gun.

These and other objects are attained by the invention, a more particular description of which will hereinafter appear and be set forth in the claims appended hereto.

In the accompanying drawing, wherein an illustrative embodiment of the invention is disclosed, Fig. 1 is a side elevation of a liquid gun constructed in accordance with the invention, the two parts of the gun body in separated relation to show how the pumping operation is performed; Fig. 2 is a side view of the gun, with one of the halves of the body of the gun removed to show the operating parts; Fig. 3 shows the trigger and valve mechanism of the device; Fig. 4 is a sectional view taken on the line 4—4 of Fig. 2; looking in the direction of the arrows, and Fig. 5 is a sectional view taken on the line 5—5 of Fig. 2, looking in the direction of the arrows.

Referring to the drawing, the body of the gun consists of two main parts, namely, the forward part 1 and the rear or stock 2. These parts may be composed of wood, plastic material or metal and need not necessarily follow the exact shape shown, but may be readily made in simulation of almost any known type of gun or rifle. These parts of the gun body may be split or divided longitudinally, the two halves being held together by screws 3 or similar fastening elements. The inner faces of the halves of the gun body parts are suitably recessed to accommodate the

5 several operating parts of the gun, one of said parts consisting of an air pump having a barrel 5 within which a piston 6 is reciprocated in the known manner of hand pumps. The piston 6 is attached to the piston rod 7 which has its end 8 connected to the cross-piece 9 of a pump-operating yoke 10 which has its opposite end 11 anchored in the stock portion 2 of the gun body. This arrangement is such that when the two parts 1 and 2 of the body of the gun are manually moved apart, or to the position shown in Fig. 1, and then brought toward one another to the closed position of Fig. 2, reciprocation of the pump piston 6 will occur and air will be forced 10 from the pump through an outlet pipe 11 and past the check valve 12 located therein and into the water tank or reservoir 13.

The water tank or reservoir 13 contains the water 14 or other liquid to be ejected or sprayed 20 from the gun. The outlet pipe through which the water is ejected is shown at 15, the same having a lower portion located within the tank and having its lower end located near the bottom of the tank. This pipe passes upwardly and through the 25 top wall 16 of the tank and enters into the part 1 of the body of the gun and then extends horizontally, as at 25, to the front end of the gun. Located in the pipe 15 is a valve 17 which is normally held in closed position by means of the spring 18. The valve 17 is provided with a head 19 which is located in the path of a valve-operating pin 20, pivotally connected at 21 to the upper end of the trigger 22.

The trigger 22 is pivoted on a pivot pin 23, 35 mounted in the stock portion 2 of the gun and the trigger is spring-pressed by the spring 24 to normally inoperative position, as shown in Fig. 3 so that its operating pin 20 is retained away from the head 19 of the valve 17, or at least does not apply sufficient pressure thereon to cause opening 40 of the valve. It will be obvious that when manual pressure is imposed upon the lower end portion of the trigger, the same will pivot on its pin 23 and the operating pin 20 will be forced forward against the head 19 of the valve 17, causing 45 the valve to be moved to open position, whereupon the water 14, under the pressure of air previously pumped into the tank or reservoir 13, will be forced upwardly through the outlet pipe 15 and through the horizontal portion 25 thereof to be ejected in a stream out of the forward open end 50 26 of the part 25 of the outlet pipe. Said forward open end 26 of the outlet pipe is located at the front end of the barrel portion 27 of the gun.

55 In preparing the gun for operation, the tank or

reservoir 13 is at least partly filled with water or other liquid to be sprayed, by removing the bottom closure cap 28 and pouring the liquid into the tank. The cap 28 is then replaced and the gun is ready for operation. Air is then forced into the tank by operating the pump by separating movement of the two parts 1 and 2 of the body of the gun. This separating movement is facilitated by use of the hand grip 29, or if the tank 13 is firmly and rigidly fastened to the forward part 1 of the gun, the tank may be gripped in one hand, and the handpiece 30 in the other, to move the parts 1 and 2 apart and together a number of times to build up air pressure in the tank 13. When the pump has been operated a few times in the manner described, the ejection of the water will take place out of the outlet end 26 each time the trigger 22 is pressed, until the air pressure in the tank 13 decreases and renewed pumping is required. When a considerable amount of air pressure is built up in the tank 13, a stream of water will be ejected for a considerable distance, and since the tank may be arranged to contain a substantial quantity of the liquid, the gun may be repeatedly used until the liquid is depleted. It may then readily be re-filled as previously described.

While I have shown the gun in a certain shape and form, it will be understood that this is merely for the purpose of illustration since the gun and its operating parts are capable of numerous changes. For example, the tank 13 may be shaped and sized to appear as a handle portion or as a fitting on the forward part of the gun; the body of the gun may be of a shape and style to resemble any well-known make of guns, and various other changes may be made without departing from the spirit of the invention as expressed in the claims appended hereto.

What I claim is:

1. A water gun comprising, a two-part gun body, one of said parts forming a barrel part and the other forming the stock, an air pump carried by the barrel part, a liquid-holding tank also carried by said barrel part, a conduit establishing communication between the pump and the tank whereby operation of the pump will force air under pressure into the tank, pump-operating means carried by the stock part of the gun body and caused to operate the pump when one part of the body is moved in a direction away from the other part of the gun body, an outlet

pipe leading out of the forward end of the gun body, a valve for controlling the flow of liquid from said tank to said pipe, and trigger means carried by the stock part of the gun body for opening said valve to cause a stream of liquid to be ejected out of the outlet tube.

2. A water gun comprising, a gun body having a forward part and a stock part, a pump carried within the forward part, a yoke attached to the stock part and extending into and slidably within the forward part, the pump having a piston, the yoke being coupled thereto whereby separating movement of the forward and stock parts of the gun body causes movement of the piston within the pump, an outlet leading from the pump, a water tank to which said outlet is connected, a valve between said outlet and the tank, a spray tube having one end located in the tank and its other end leading out of the front end of the forward part of the gun body, a valve in said spray tube, and trigger means carried by the stock part for opening the last-mentioned valve.
3. A water gun comprising a gun body having a forward part and a stock part, a pump carried within the forward part, a yoke attached to the stock part and extending into and slidably within the forward part, the pump having a piston, a rod extending from the piston, the yoke being coupled to the rod whereby separating movement of the forward and stock parts of the gun body causes movement of the piston within the pump, an outlet pipe leading from the pump, a water tank to which said outlet pipe is connected, a valve between said outlet pipe and the tank, a spray tube having one end located within the tank and its other end leading out of the front end of the forward part of the body, a valve in said spray tube between its forward end and the tank, and a spring-pressed trigger carried by the stock part and manually operable to open the last-mentioned valve.
